UNITED STATES PATENT OFFICE.

WILLIAM A. DISOTELL, OF BELVIDERE, ILLINOIS.

HOT-AIR FURNACE.

SPECIFICATION forming part of Letters Patent No. 689,859, dated December 31, 1901.

Application filed April 22, 1901. Serial No. 56,995. (No model.)

To all whom it may concern:

Be it known that I, WILLIAM A. DISOTELL, a citizen of the United States of America, residing at Belvidere, in the county of Boone 5 and State of Illinois, have invented certain new and useful Improvements in Hot-Air-Furnaces, of which the following is a specification.

The object of my invention is to improve the interior construction of hot-air furnaces by so combining and arranging therein in a novel manner radiators, hot-air flues, a smoke-flue, a smoke-conduit, and a damper as to sufficiently retard the escape of the products 15 of combustion from the combustion-chamber thereof to insure the largest possible elimination of heat therefrom; and it consists of certain new and useful features of construction and combinations of parts hereinafter fully 20 described, and specifically pointed out in the claims.

Referring to the accompanying drawings, which form a part of this specification, Figure 1 is a central vertical section of a furnace embodying my improvements. Figs. 2, 3, and 4 are horizontal sections through the dotted lines 2, 3, and 4, respectively, in Fig. 1 of parts there shown. Fig. 5 is a sectional detail showing a form of joint employed for connecting the air-flues with the drum-radiator and lower portion of the combustion-chamber and also with the dome of the furnace.

Like letters of reference indicate corresponding parts throughout the several views. 35 A is the jacket of the furnace, which is provided with hot-air-exit pipes A' and a cold-air-inlet duct A².

B is a combustion-chamber having a plurality of openings B' in the lower end B² thereof 40 of and closed at its apex by means of a dome B³, also having a plurality of openings B⁴ therein.

B⁵ is a fire-pot integral or rigidly connected with the large central opening B⁶ in the lower 45 end B² of the combustion-chamber B.

B⁷ B⁸ represent an ash-pit and grate located immediately below the fire-pot B⁵.

C is a drum-radiator having openings C' C² in its upper and lower heads C³ C⁴, corresponding in number and position with the 50 openings B⁴ B' in the dome B³ and lower end B² of the combustion-chamber B, respectively.

D represents air-flues connecting the openings B' in the lower end B² of the combustion-chamber B with corresponding openings 55 C² in the lower head C⁴ of the drum-radiator C.

E represents air-flues connecting the openings B⁴ in the dome B³ with the corresponding openings C' in the upper head C³ of the 60 drum-radiator C.

F is an air-flue extending from a central opening F' in the upper head C³ of the drum-radiator C, through the dome B³ and a smoke-conduit, to be described hereinafter, into the 65 air-chamber formed by the jacket A of the furnace.

G is a tubular radiator bisected by means of a smoke-conduit G', opening thereinto and combined therewith. 70

H is a smoke-flue connecting an opening H' in the dome B³ with an opening H² in the smoke-conduit G'.

I is a damper in the smoke-conduit G' for deflecting smoke therefrom through the tubular radiator G. 75

J is a pipe connecting the interior of the combustion-chamber B through a suitable chimney with the outer air.

J' is a damper located in the pipe J. 80
K K' are clean-outs.

The air-flue D, Fig. 5, has an annular recess D' formed in the end thereof concentric therewith. The hole C² in the plate C⁴—the lower head of the drum-radiator C—opens 85 into and coincide with the air-flue D and is surrounded by an integral annular flange C⁵, projecting into and included in the annular recess D' in the end of the air-flue D, and cement L seals the flange C⁵ into the annular 90 recess D', thereby forming a smoke-tight joint between the flue D and the opening C² in the bottom C⁴ of the drum-radiator C. All the air-flues D and E are united in like manner with the parts with which they are connected. 95

The construction of the combustion-chamber B and the arrangement therein of the air-flues D, the drum-radiator C, and air-flues E as herein shown and described so retards the 100 escape of the products of combustion throughout as to eliminate therefrom the largest possible amount of heat practicable. The employment of the smoke-flue H, tubular radi-

ator G, smoke-conduit G', and damper I also results in a still further elimination of heat from the ascending and escaping products of combustion.

5 In Fig. 1 of the drawings the broken arrows indicate the movements of the hot air and the solid arrows the movements of the volatile products of combustion.

What I claim as new, and desire to secure 10 by Letters Patent, is—

1. In a hot-air furnace, in combination, a combustion-chamber, having a plurality of openings, in the lower end thereof, and closed, at its apex, by means of a dome also having a 15 plurality of openings therein, a drum-radiator—included within the combustion-chamber—having openings, in its upper and lower heads, corresponding, in number and position, with the openings, in the dome and 20 lower portion of the combustion-chamber, respectively, a series of air-flues, connecting the openings in the lower end of the combustion-chamber with the corresponding openings in the lower head of the drum-radiator, a 25 series of air-flues, connecting the openings in

the dome with the corresponding openings in the upper head of the drum-radiator, and an air-flue, extending from a central opening in the upper head of the drum-radiator, through the dome and smoke-conduit, into the air- 30 chamber formed by the jacket of the furnace, substantially as and for the purpose specified.

2. In a hot-air furnace, in combination, a combustion-chamber, closed at its apex by means of a dome, a tubular radiator—bi- 35 sected by means of a smoke-conduit opening thereinto and combined therewith—located above the dome, a smoke-flue connecting an opening in the dome with an opening in the smoke-conduit, and a damper in the smoke- 40 conduit for deflecting smoke therefrom through the tubular radiator, substantially as and for the purpose specified.

In testimony whereof I have signed my name to this specification in the presence of 45 two subscribing witnesses.

WILLIAM A. DISOTELL.
